14 Claims. (Cl. 123—117)

This invention relates generally to ignition distributors, and more specifically to those distributors which are responsive to variations in engine speed and load.

Many designs of distributors have been proposed and tried wherein centrifugal and vacuum forces are used to regulate the timing advance and/or retard of the distributor. However, none of these have been able to combine all of the desirable features, such as (1) flexibility of calibration, (2) elimination of vacuum leakage, (3) rugged advance mechanism, (4) stationary breaker plate and (5) perfect rotor registry, into a workable embodiment.

Accordingly, it is an object of this invention to provide means whereby all of the above features can be included in an ignition distributor.

Other objects and advantages of the invention will become apparent when reference is made to the following specification and illustrations, wherein:

Figure 1 is an elevational view of an ignition distributor constructed in accordance with the invention, with portions of the distributor housing being cut away and in cross-section. Figure 1 includes a schematic illustration of the engine.

Figure 2 is a top plan view of the distributor shown in Figure 1, with the cap and rotor removed.

Figure 3 is a cross-sectional view of the distributor taken substantially on the plane of line 3—3 of Figure 1 and looking in the direction of the arrows.

Figure 4 is also a cross-sectional view of the distributor taken substantially on the plane of line 3—3 of Figure 1 looking in the direction of the arrows; Figure 4 differs from Figure 3 in that some of the elements shown in Figure 3 have been removed.

Figures 5, 6, and 7 are perspective views of some of the elements included in the preferred embodiment of the invention.

Figure 8 is a cross-sectional view taken substantially on the plane of line 8—8 of Figure 7 and looking in the direction of the arrows.

Figure 9 is a fragmentary view illustrating the pneumatic conduit employed in the invention.

Figure 10 is a schematic representation of the lever arms and forces affecting the operation of the advance mechanism embodying the invention.

Referring now in greater detail to the drawings, Figure 1 illustrates an ignition distributor 10 which communicates by means of suitable conduitry schematically illustrated at 12 with a port 14 in the carburetor 16. The carburetor 16 is located on manifold 18 in such a manner so as to deliver a combustible mixture, the flow of which is controlled by the throttle valve 20, to the individual intake ports of the cylinders located in engine 22.

The distributor 10 comprises a housing 24 including a depending reduced portion 26 having an opening 28 therethrough for the reception of a driving shaft 30. The upper end of the cup-shaped housing 24 is generally closed by a breaker plate 32 on which is mounted the breaker arm assembly 34, which includes a cam engaging

2

portion 36 engageable by the rotating cam 38 to effect make and break of the circuit at the contacts indicated at 40 (Figure 2). The cam 38 is fixedly secured to a tubular shaft 42 which is rotatable with the shaft 30 in its normal operation, but which is also angularly adjustable relative thereto to advance or retard the spark timing. An insulated rotor 44, having a spring-like electrical contact 46 thereon, is secured to the upper portion of tubular shaft 42 and is adapted to be rotated thereby normally in accordance with engine speed. Contact 46, which is continually biased against the ignition coil input terminal 48 of the distributor cap 49, is adapted to sequentially traverse the output terminals 50 of cap 49 (of which only one is shown) and is so positioned that the two are in juxtaposition whenever the electrical discharge occurs.

Shaft 30 has a conduit 52 formed therein which communicates between the vacuum responsive advance mechanism, to be described later, and the conduitry 12 by means of a radially formed conduit 54, chamber 56 and the horizontal conduit 58. Chamber 56, formed generally by bushing 60 and depending portion 26, has seals 62 and 64 therein which are displaced by suitable retainers 66 and a spring member 68. The seals are provided in order to prevent any possible vacuum leakage between the shaft 30 and any coating elements such as portion 26. The shaft 30 is of course driven in accordance with engine speed as by means of gear 70.

Figure 3 illustrates in plan view the general arrangement of the advance mechanism. A base plate 72, which is rigidly secured to shaft 30 through a bushing member 74 (see Figure 1 also), carries diametrically opposed pins 76 and 78 which are fixed therein so as to be parallel to shaft 30. These pins 76 and 78 provide pivoted supports for the advance devices indicated generally at 80 and 82. It may be well to note at this time that the fact that different numerals are used to identify apparently identical elements should not be construed to imply that the elements are different. For reasons which will become obvious later in the specification, individual elements, regardless of whether or not they are identical or similar to others, are identified with their own specific reference numbers.

The advance devices 80 and 82 have extending arm portions 84 and 86, respectively, which in turn are pivotably mounted at 76 and 78 by means of sleeve members 88 and 90. A cam plate 92, which is rigidly secured to the lower portion of tubular shaft 42, is connected to the advance devices, as by means of downwardly extending pins 94 and 96 which are secured to the plate 92. The motion transmitting links 98 and 100 extending from the devices 80 and 82 are adapted to coat with pins 94 and 96, as by means of sleeve portions 102 (see Figure 4 also), in order to ultimately determine the degree of advance or retard of cam 38 (Figure 1).

Figure 4 is a sectional plan view similar to Figure 3 except that cam plate 92, tubular shaft 42, the advance device 80 and pin 76 have been removed for purposes of clarification. A curve plate 104, having a collar portion 106, is mounted on shaft 30 in such a manner so as to have freedom of angular movement with respect to said shaft. Calibrating springs 108 and 110 are secured at one end to adjustable tabs 112 and 114; the other ends of the springs are fastened to arms 116 and 118 of the curve plate 104. The curve plate 104 also has another pair of diametrically opposed arms 120 and 122 which are adapted to be continually in contact with levers 124 and 126. The contacting surfaces 128 and 130 (Fig. 6) of arms 120 and 122 are developed so that the advance mechanism will meet the particular calibration requirements of an engine, while the contacting surfaces 132 and 134 of levers 124 and 126 are preferably made straight.

Figure 7 better illustrates the advance device 80. Lever 126 is rigidly secured in any suitable manner to the arm 84 near the pivoted end thereof. A projection 136 extends from the under side of arm 84 and serves to hold an adapter member 140 which is in effect a short conduit which communicates with conduit 12 in a manner to be later described. It should be mentioned that the advance device 80 illustrated is identical to the device 82.

Figure 8, a substantially cross-sectional view of Figure 7, illustrates the details within the advance device 80. The device 80 is generally comprised of a housing 138 which retains a diaphragm 142 therein by virtue of suitable means such as the rim flange portion 144. A cover plate 146 is provided in order to prevent possible damage to the diaphragm 142. An upwardly extending, internally threaded collar portion 143 is secured to the housing 138 opposite the diaphragm 142. An adjustable spring abutment 150 having externally formed threads coacts with collar 143 and spring 152 to bias the diaphragm 142 outwardly. Axial adjustment of abutment 150 can be made by inserting suitable shims, as illustrated at 154, between itself and collar 143. Shims of course may be placed between spring 152 and abutment 150 if so desired.

During periods of operation when the vacuum in chamber 162 is not sufficient to move diaphragm 142, the spring 152 biases the diaphragm outwardly causing the diaphragm clamp plate 156 to contact cover plate 146. The motion transmitting link 98 may be secured to the diaphragm 142 as by means of oppositely disposed plates 156 and 158.

The arm portion 84 has a conduit 160 formed therein which communicates with chamber 162, formed generally by housing 138 and diaphragm 142, by means of a port 164 in housing 138. A flexible conduit 166, which communicates with a source of vacuum, is adapted to be externally received by conduit portions 140 which, in turn, communicates with conduit 160 as by a passageway 168 formed in both arm 84 and portion 136 (see Figure 7 also).

Operation

Referring to Figure 3, let it be assumed that the engine is running at curb idle and the spark advance mechanism is in full retard. Under these conditions, the elements would assume positions as illustrated in Figure 3.

Springs 108 and 110 being anchored at one end to the base plate 72, which is in turn secured to shaft 30, urge the curve plate 104 (see Fig. 4) in a counterclockwise direction by virtue of their connection to arms 116 and 118. When the curve plate 104 is urged in this direction, it causes the advance devices 80 and 82 to be urged in a clockwise direction about their respective pivots 76 and 78 by virtue of the cooperative action between arms 122 and 120 of curve plate 104 and levers 126 and 124 secured to the advance devices 80 and 82, respectively.

The advance devices will move in a clockwise direction, until the truncated portion 176 of covers 146 abut against the trailing edges of levers 124 and 126. At this time, the cam 38 (Figure 1) will have been rotated clockwise to its full retard position by virtue of tubular shaft 42, cam plate 92, and the connection between the motion transmitting links 98 and 100 and the pins 94 and 96 secured to cam plate 92.

As engine speed increases, the rotational speed of shaft 30 will correspondingly increase, and the weighted advance devices 80 and 82 will travel arcuately outwardly about their pivoted ends 88 and 90. As the advance devices 80 and 82 move outwardly, the motion transmitting links 98 and 100 rotate cam plate 92 and cam 38 counterclockwise with respect to shaft 30, thereby causing an advance which is generally related to the increase in speed. The forces which restrict outward movement of the advance devices are ultimately due to the resistance offered by the tension springs 108 and 110.

5 In order to modulate the normal centrifugal forces of the advance devices 80 and 82, a curve plate 104 (Figures 3 and 4) is employed. Generally speaking, the centrifugal forces of the advance devices increase as the square of the speed, and the desired result is to have displacement due to the centrifugal forces increase, at the most, in a linear fashion with respect to speed. This result is obtained by proper calibration of the curve plate 104.

10 Referring principally to Figure 4, it is seen that the resisting forces of the springs 108 and 110 are transmitted to the advance devices 80 and 82 through the curve plate 104, as by means of arms 116 and 118, arms 120 and 122 and levers 124 and 126, which are made functionally integral with the advance devices.

15 Figure 10 illustrates schematically the mechanics of the force compensating mechanism employed. As the speed of rotation about shaft 30 increases, the excessive centrifugal forces, F_w , are overcome by the tension (F_s) of spring 108; this is accomplished by creating a greater effective spring force through means continually changing the effective lever arms, as from points A to B to C. The principle of varying effective forces by varying intermediate lever arms is well known; however, the means by which this principle is practiced in the present invention 20 is a considerable improvement over that which is presently considered to be general practice.

25 For purposes of illustration, let it be assumed that the elements of Figure 10 are at a condition of equilibrium when the arms 120 and 124 are tangent at point A and that the following are true:

- 30 (1) F_w = centrifugal force of mass 82.
 (2) L_w = lever arm of centrifugal force F_w .
 (3) L_{c1} = lever arm of arm 124.
 (4) L_{c2} = lever arm of arm 120.
 (5) F_1 = the unresolved component of the normal resulting force opposing arms 120 and 124 at point A.
 (6) F_s = force of spring 108.
 (7) Δ_s = deflection of spring 108.
 (8) K_s = spring constant of spring 108.
 (9) L_s = lever arm of spring force F_s .
 (10) Δ_m = movement of mass 82 corresponding to Δ_s .

35 From the above, the following relationships exist:

$$40 (1) F_w(L_w) = F_1(L_{c1})$$

and

$$45 (2) F_1(L_{c2}) = L_s(K_s)(\Delta_s)$$

or since K_s and L_s are constants,

$$50 (3) \Delta_s = K_1(F_1)(L_{c2})$$

Accordingly,

$$55 (4) \frac{\Delta_s}{L_{c2}} = \frac{\Delta_m}{L_{c1}}$$

or:

$$60 (5) \Delta_m = \frac{L_{c1}}{L_{c2}} \Delta_s$$

65 From the above, it is apparent that the force of spring 108 is not only a function of the centrifugal force but also a function of the ratio of the lever arms L_{c1} and L_{c2} of members 124 and 120, respectively. This ratio, which changes when L_{c1} and L_{c2} change in equal and opposite amounts can, of course, be controlled by contouring the edges 122 and 128 to any required shape.

70 When the throttle valve 20 is opened, a source of vacuum is made available at port 14 for the regulation of the cam 38 in accordance with engine vacuum. Referring now to Figures 1, 4, 7, 8, and 9, the vacuum is transmitted from port 14 through conduits 12, 58, 52, 170 to tubular projections 172 and 174, which are pneumatically connected to flexible conduits 166 and 167, respectively. The other ends of conduits 166 and 167

are connected to adapted members 140 on arms 84 and 86 in such a manner so as to communicate with conduits 160 and chambers 162 of the advance devices 80 and 82.

Assuming now that the advance devices have been positioned in accordance with engine speed, any part throttle position will cause vacuum to be communicated to chambers 162 and accordingly move the diaphragm 142 inwardly against the force of spring 152. The maximum advance is, of course, when the diaphragm assembly abuts against the stop 150.

Referring to Figure 8, it becomes apparent that the vacuum advance is completely independent from that of the speed advance and therefore lends itself readily to a practical embodiment.

In summarizing the advantages of the invention, it can be pointed out that the curve plate 104 which controls the speed advance is interchangeable. That is, it is a loose piece which can easily be removed for replacement or recalibration without any rework of the distributor, as is required by present distributors employing a curve plate. Further, there is perfect rotor registry at all speeds even though there are independent controls for cam advance in accordance with engine speed and vacuum. Perfect rotor registry of course, refers to the fact that the rotor 44 and contact 46 are in juxtaposition to the output terminals 50 whenever an electrical discharge occurs. This result is obtained by virtue of the cam 38 being rotated by the advance mechanism instead of the breaker arm assembly, as is conventional in distributors responsive to vacuum. Perfect rotor registry provides for proper distribution of electrical discharges and prevents any misfiring or "cross-firing" as between any two successive output terminals as indicated at 50. In addition, the construction is one which has no vacuum leakage and at the same time exhibits a high degree of sensitivity to changes in control parameters.

Although only one embodiment has been disclosed, it is apparent that other modifications are possible without exceeding the scope of the appended claims.

What we claim as our invention is:

1. In an ignition distributor for an internal combustion engine having an induction passage, a drive shaft adapted to be driven in accordance with engine speed, a cam member coaxial with said shaft and adapted to be angularly adjustable relative thereto, means responsive to changes of engine operating conditions for adjusting said cam member relative to said shaft, said means combining speed responsive elements and pressure responsive elements, said speed responsive elements being capable of independently adjusting said cam in response to variations in engine speed, and a floating generated calibration plate for modifying the action of said speed responsive elements, said pressure responsive elements being capable of independently adjusting said cam in response to variations in induction passage vacuum regardless of engine speed and without moving said speed responsive elements or influencing said calibration plate in any way.

2. In an ignition distributor for an internal combustion engine having an induction passage, a housing, a shaft mounted through one end of said housing for rotation therein in accordance with engine speed, a base plate mounted on said shaft and disposed normally thereto, a cam member normally rotatable with said shaft for effecting a make and break of the ignition circuit, a cam plate rigidly secured to said cam member, a plurality of diametrically disposed pivotal support members located within said base plate, weights pivotally mounted on said support members and adapted to have arcuate movement in response to variations in engine speed, a plurality of springs each anchored at one end to said base plate, lever arms secured to said weights at the pivotally mounted ends, a floating curve plate mounted on said shaft and having secured thereto the other ends of said springs, said curve plate and said levers being positioned so as to be in substantial juxtaposition to

each other and always in contact with each other, and means connecting the free ends of said pivotally mounted weights and said cam plate for rotating said cam plate and said cam member in accordance with engine speed.

3. In an ignition distributor for an internal combustion engine having an induction passage, a housing, a shaft mounted through one end of said housing for rotation therein in accordance with engine speed, a base plate mounted on said shaft and disposed normally thereto, a cam member normally rotatable with said shaft for effecting a make and break of the ignition circuit, a cam plate rigidly secured to said cam member, a plurality of diametrically disposed pivotal support members extending from said base plate, weights pivotally mounted on said support members and adapted to have arcuate movement in response to variations in engine speed, a plurality of springs anchored each at one end to said base plate, lever arms secured to said weights at the pivotally mounted ends, a floating generated calibration plate mounted on said shaft having secured thereto the other ends of said springs, said calibration plate and said levers being positioned so as to be in substantial juxtaposition to each other and always in contact with each other, and means connecting the free ends of said pivotally mounted weights and said cam plate for normally rotating said cam plate and said cam member in accordance with engine speed.

4. In an ignition distributor for an internal combustion engine having an induction passage, a housing, a shaft mounted through one end of said housing for rotation therein in accordance with engine speed, a base plate mounted on said shaft and disposed normally thereto, a cam member normally rotatable with said shaft for effecting a make and break of the ignition circuit, a cam plate rigidly secured to said cam member, a plurality of diametrically disposed pivotal support members located within said base plate, weights pivotally mounted on said support members and adapted to have arcuate movement in response to variations in engine speed, a plurality of springs anchored at one end to said base plate, lever arms secured to said weights at the pivotally mounted ends, a floating generated calibration plate mounted on said shaft having secured thereto the other ends of said springs, said calibration plate and said levers being positioned so as to be in substantial juxtaposition to each other and always in contact with each other, and means connecting the free ends of said pivotally mounted weights and said cam plate for both normally rotating said cam plate and said cam member in accordance with engine speed and for rotating said cam member relative to said shaft.

5. In an ignition distributor for an internal combustion engine having an induction passage, a housing, a shaft mounted through one end of said housing for rotation therein in accordance with engine speed, a base member mounted on said shaft and disposed normally thereto, a cam member normally rotatable with said shaft for effecting a make and break of the ignition circuit, a cam plate rigidly secured to said cam member, a plurality of pivotal support members extending from said base member, weights pivotally mounted on said support members and adapted to have movement in response to variations in engine speed, a plurality of springs anchored at one end to said base member, lever arms secured to said weights at the pivotally mounted ends, a floating calibration plate mounted on said shaft having secured thereto the other ends of said springs, said calibration plate and said levers being positioned so as to be in substantial juxtaposition to each other and always in contact with each other, and means connecting the free ends of said pivotally mounted weights and said cam plate for both normally rotating said cam plate and said cam member in accordance with engine speed and for rotating said cam member relative to said shaft.

6. In an ignition distributor for an internal combustion

7
engine having an induction passage, a housing, a shaft mounted through one end of said housing for rotation therein, a base plate mounted on said shaft and disposed normally thereto, a cam member normally rotatable with said shaft for effecting a make and break of the ignition circuit, a plate rigidly secured to said cam member, a plurality of diametrically disposed pivotal support members extending from said base plate, weights pivotally mounted on said support means and adapted to have arcuate movement in response to variations in engine speed, a plurality of springs each anchored at one end to said base plate, lever arms secured to said weights at the pivotally mounted ends, a floating curve plate mounted on said shaft having secured thereto the other ends of said springs, said curve plate and said levers being so positioned so as to be in substantial juxtaposition to each other and always in contact with each other, and means connecting the free ends of said pivotally mounted weights and said plate secured to said cam member for rotating said plate and said cam member in accordance with engine speed.

7. In an ignition distributor for an internal combustion engine having an induction passage, a shaft adapted to be rotated in accordance with engine speed, a cam normally rotated with said shaft, advance devices for adjusting said cam relative to said shaft in accordance with variations in engine conditions, said advance devices comprising speed responsive centrifugal weights biased by constant rate springs and vacuum responsive means normally biased by separate constant rate springs, common means connecting said speed responsive weights and said vacuum responsive means to said cam, and floating centrifugal force modifying means interposed between said first mentioned constant rate springs and said speed responsive weights for diminishing said centrifugal force to an effective one which increases at the most in a linear fashion with respect to engine speed.

8. In an ignition distributor for an internal combustion engine having an induction passage, a shaft adapted to be rotated in accordance with engine speed, a cam normally rotated with said shaft, advance devices for adjusting said cam relative to said shaft in accordance with variations in engine conditions, said advance devices comprising speed responsive centrifugal weights biased by constant rate springs and vacuum responsive means normally biased by separate constant rate springs, common means connecting said speed responsive weights and said vacuum responsive means to said cam, and floating centrifugal force modifying means interposed between said first mentioned constant rate springs and said speed responsive weights for varying the effectiveness of said first mentioned constant rate springs so that the effective resisting force thereof approaches a value which varies as the square of the speed of said shaft.

9. In an ignition distributor for an internal combustion engine having an induction passage, a shaft adapted to be rotated in accordance with engine speed, a cam normally rotated with said shaft, advance devices for adjusting said cam relative to said shaft in accordance with variations in engine conditions, said advance devices comprising speed responsive centrifugal weights biased by constant rate springs and vacuum responsive means normally biased by separate constant rate springs, common motion transmitting means connecting said speed responsive weights and said vacuum responsive means to said cam, and floating centrifugal force modifying means interposed between said first mentioned constant rate springs and said speed responsive weights for modifying the movement of said weights to a rate which is consistent to an advance of said cam which increases at the most in a linear fashion with respect to engine speed.

10. In an ignition distributor for an internal combustion engine having an induction passage, a drive shaft adapted to be driven in accordance with engine speed, a cam member coaxial with said shaft and adapted to be

5 angularly adjustable relative thereto for the purpose of advancing and retarding the ignition, means responsive to changes in engine operating conditions for adjusting said cam member, said means including engine speed responsive and engine vacuum responsive elements, said elements comprising a transverse member mounted to rotate with said shaft, arm members pivotally mounted on said transverse member, speed responsive weight members at the outer ends of said arms, said weight members having said vacuum responsive elements formed therein, said weight members and said vacuum responsive elements both being spring biased and being connected serially to said cam member, said connection including a member mounted on said shaft and having calibrated cam surface for modifying the centrifugal force due to said weight members, said latter member being pivotally mounted on said shaft so as to be readily removable and replaceable with a member having a different cam surface so as to effect a change in speed response calibration.

10 11. In an ignition distributor for an internal combustion engine having an induction passage, a drive shaft adapted to be driven in accordance with engine speed, a cam member coaxial with said shaft and adapted to be angularly adjustable relative thereto for the purpose of advancing and retarding the ignition, means responsive to changes in engine operating conditions for adjusting said cam member, said means including engine speed responsive and engine vacuum responsive elements, said elements comprising a member mounted to rotate with said shaft, speed responsive weight members pivotally mounted on said last named member, said weight members including said vacuum responsive elements formed at the free ends thereof, said weight members and said vacuum responsive elements being separately spring biased and being connected to said cam member in a manner so as to be capable of independent adjustment of said cam member, said connection including a member mounted on said shaft and having a calibrated cam surface for modifying the centrifugal force due to said weight members, said latter member being pivotally mounted on said shaft so as to be readily removable and replaceable to effect a change in speed response calibration.

15 12. In an ignition distributor for an internal combustion engine having an induction passage, a drive shaft adapted to be driven in accordance with engine speed, a cam member coaxial with said shaft and adapted to be angularly adjustable relative thereto for the purpose of advancing and retarding the ignition, means responsive to changes in engine operating conditions for adjusting said cam member, said means including engine speed responsive and engine vacuum responsive elements, said elements comprising a cross member mounted to rotate with said shaft, weight members pivotally mounted on said cross member, said weight members having said vacuum responsive elements formed at the free ends thereof, said weight members and said vacuum responsive elements both being spring biased and being connected to said cam member in a manner so as to be capable of independent adjustment of said cam member, the spring bias of said vacuum responsive elements being adjustable, said connection including a member mounted on said shaft and calibrated cam surfaces for modifying the effect of said weights, said latter member being pivotally mounted on said shaft so as to be readily removable and replaceable to effect a change in speed response calibration.

20 13. In an ignition distributor for an internal combustion engine having an induction passage, a drive shaft adapted to be driven in accordance with engine speed, a cam member coaxial with said shaft and adapted to be angularly adjustable relative thereto for the purpose of advancing and retarding the ignition, means responsive to changes in engine operating conditions for adjusting said cam member, said means including engine speed responsive and engine vacuum responsive elements, said vacuum responsive elements including stop means to limit the ignition

advance in response to engine vacuum, said elements comprising a lateral member mounted to rotate with said shaft, weight members pivotally mounted on said lateral member, said weight members having said vacuum responsive elements secured to the free ends thereof, said weight members and said vacuum responsive elements both being spring biased and being connected in series to said cam member in a manner so as to be capable of independent adjustment of said cam member, said connection including a member mounted on said shaft and including calibrated cam surface for modifying the effect of said weights, said latter member being pivotally mounted on said shaft so as to be readily removable and replaceable to effect a change in speed response calibration.

14. In an ignition distributor for an internal combustion engine having an induction passage, a drive shaft adapted to be driven in accordance with engine speed, a cam member coaxial with said shaft and adapted to be angularly adjustable relative thereto for the purpose of advancing and retarding the ignition, means responsive to changes in engine operating conditions for adjusting said cam member, said means including engine speed responsive

and engine vacuum responsive elements, said elements comprising a transverse member mounted to rotate with said shaft, speed responsive weight members pivotally mounted on said transverse member, said weight members having said vacuum responsive elements secured to the free ends thereof, said weight members and said vacuum responsive elements both being spring biased and being connected to said cam member in a manner so as to be capable of independent adjustment of said cam member, said connection including a member mounted on said shaft and having calibrated cam surface for modifying the effect of said weights, the vacuum connection between said induction passage and vacuum responsive elements being through said shaft and said weight members and including a flexible conduit so as to require only a single rotary vacuum seal at said shaft.
